UNITED STATES PATENT OFFICE.

JAMES HILL, OF PROVIDENCE, RHODE ISLAND.

IMPROVED TAGGED BRAID FOR SHOE-STRINGS.

Specification forming part of Letters Patent No. 38,164, dated April 14, 1863.

To all whom it may concern:

Be it known that I, JAMES HILL, a citizen of the United States of America, and a resident of the city and county of Providence, and State of Rhode Island, have invented an Improved Manufacture of Shoe-String Tagged Braid; and I do hereby declare the same to be fully described in the following specification, and represented in the accompanying drawing, of which—

The nature of my invention consists in a piece or strip of braid or cord having at suitable intervals apart and encompassing it a series of bands or tubes of metal, each of which is double or about double the length required for a tag, and so that by cutting each of the said bands or tubes in two or severing it at its middle the whole piece or strip may be reduced to shoe-strings provided with tags at their ends.

Previous to my invention it has been customary to prepare the tags of the proper length for use on a shoe-string and apply them thereon by hand, and on a short piece of braid or a piece of the proper length for a shoe-string.

In the production of my invention the double-tag blanks may be put on the braid, either by manual labor or by a machine suitably made for the purpose, and after the band may have been so prepared each tag-blank should be cut across at its middle, and the two tags thus formed out of each blank should be pointed.

I do not claim a shoe-string composed of a piece of braid or cord and two tubular tags affixed upon it at its two ends; but

What I do claim as my invention is—

The above-described improved manufacture of double-tagged braid capable of being made into tagged shoe-strings by severing each double-tag blank at its middle, as specified.

JAMES HILL.
